BAG LOADING OR FILLING DEVICE

Ralph W. E. Nash, Nashua, N. H.

Application August 19, 1941, Serial No. 407,481

6 Claims. (Cl. 226—18)

This invention relates to improvements in filling devices and pertains particularly to a device for facilitating the introduction of material into a receiving container.

In the packaging of materials such as stacks of paper napkins or bolts of cheesecloth, sheets, pillowcases etc. use is made of bag-like wrappers, one end of which is closed while the other end is open to receive the material. When handling materials of the soft nature of those above referred to, some difficulty is experienced in sliding the materials into the container or wrapping receiver.

In view of the foregoing, the present invention has for its principal object to provide a loading device which may be employed to facilitate guiding the material into the receiving wrapper so that the material will be neatly and tightly wrapped and will not be folded in any way or mussed in getting it into the container.

Another and more specific object of the invention is to provide a loading device for facilitating introduction of soft materials into a wrapping bag or receiver, which comprises a pair of members which cooperate to form a funnel-like structure which is introduced at one end into the wrapping bag and operates to guide the material therewith.

Still another object is to provide in a device of the character stated, a pair of cooperating members which combine to form a funnel-like guide, in which one of the members is fixed and the other is movable relative thereto so as to facilitate the loading into receiving bags or wrappers of bundles of material of different sizes.

The invention will be best understood from a consideration of the following detailed description taken in connection with the accompanying drawing, it being understood however, that the invention is not to be considered as limited by the specific illustration or description but that such illustration and description constitutes a preferred embodiment of the invention.

In the drawing:

Fig. 1 is a view in top plan of the device embodying the present invention.

Fig. 2 is a longitudinal sectional view of the same on the line 2—2 of Fig. 1.

Fig. 3 is a view in perspective of the device mounted upon a supporting board and showing the manner of using the device for introducing a bundle of folded articles into a receiving bag.

Referring now more particularly to the drawing, it will be seen that the present device comprises a base supporting bar 1 which is turned

downwardly at each end, as indicated at 2, and is attached to a foot plate 3. The plates 3 are designed to be secured to a suitable supporting table or baseboard 4, as shown in Fig. 3. At each 5 end of the bar 1, there is secured an upstanding or vertical post 5 which is provided with a longitudinally extending slot 6. Upon the outer side of each post 5 there is secured above the slot 6, an outwardly projecting pin 7, the purpose of 10 which will be hereinafter described.

Disposed between the posts 5 is a unitary structure having a funnel-like function for the guiding of materials into a wrapping bag or receiver such as is indicated by the numeral 8. This 15 structure is indicated as a whole by the numeral 9 and comprises a lower portion or chute 10 fixed to the posts 5 and a movable upper portion or damper 11. The chute 10 comprises a bottom 12 of substantial length which extends across and 20 rests upon the bottom bar 1 and the bottom merges into the upturned side walls or flanges 13, which are cut off obliquely at their forward ends, as indicated at 14. The rear portion of the bottom 12 slopes slightly downwardly, as indicated at 15, and terminates in a gradual downwardly curved lip 16 and the rear ends of the flanges 13 terminate in the outwardly curving or rounded lips 17 which are continuations of the lip 16, as will be clearly seen upon reference 25 to Figs. 1 and 3 particularly. The rear end of the chute is thus provided with a relatively wide entrance mouth for guiding a bundle or stack of folded articles into the chute, such a stack of folded articles being shown in Fig. 3 and indicated 30 by the reference character A.

The damper 11 comprises an elongated metal plate 18 which is of less length than the chute 10 and also of less width. The plate 18 is turned at its opposite longitudinal edges to form the 40 shallow flanges 19 and at its rear end the plate is curved upwardly to form the guide lip 20 which coacts with the lip 16 and the side wall lips 17 to form an entrance mouth to the device. The damper 11 is disposed within and 45 between the side flanges or walls of the chute and adjacent the rear end thereof there extends across the damper and is secured to the top thereof, a supporting and pivot rod 21, the ends of which extend through the slots 6 of the adjacent posts 5. Any suitable means may be employed for securing this rod 21 to the back of the plate 18, the means here shown consisting of a strip of metal 22 which is longitudinally 50 channeled to receive the pivot bar 21 and which 55

is riveted at opposite sides of the channel to the plate 18, as indicated at 23.

Upon the outer sides of the uprights 5, the ends of the bar 21 have connected therewith contractile springs 24 which are attached to the overlying pins 7 and these springs constantly draw the bar upwardly to lift the rear end to its uppermost position away from the chute 10.

While the structure illustrated has the pins 7 lying above the slots 6, it is contemplated as being within the scope of this invention to also locate these pins below the slots so that the springs 24 may also function to draw the bar downwardly. This positioning of the springs will be governed by whether the loader is high or low, and if it is high the springs are placed below the slots so that the goods will not hit the damper at the wrong angle.

What is claimed is:

1. A device of the character stated, comprising a relatively long chute-like body having a bottom and side walls, means for horizontally supporting said body, a pair of standards disposed vertically adjacent one end of the body and having the body located therebetween, the said one end of the body having the bottom and side walls curved outwardly, an elongated plate having an overall width slightly less than the width of the space between said side walls, said plate being located adjacent one end between the standards, said standards having vertical slots therein above the chute body, a trunnion means at each side of the plate extending through the adjacent standard slot to rotate and to move vertically therein, said plate at the said one end being curved outwardly to form a lip cooperating with the outwardly curved portions of the bottom and side walls to form a funnel mouth, the other end of the plate extending downwardly into and resting upon the bottom of the chute, and spring means connecting each of said trunnions with the adjacent standard above the slot therein and normally urging the adjacent end of the plate upwardly away from the chute.

2. A container filling device, comprising an elongated horizontally disposed body having longitudinal side walls, a pair of fixed standards disposed upon opposite sides of the body,

an elongated plate extending lengthwise over the body and disposed between said standards, and a pivotal coupling between said plate and the standards for oscillation of the plate on an axis extending transversely of the body, said pivotal coupling between the plate and the standards being constructed and arranged to provide means to allow the plate to have free movement longitudinally of the standards whereby the plate and body are movable relatively toward and away from one another simultaneously with the oscillation of the plate on said axis.

3. A container filling device as set forth in claim 2, including springs operatively coupling the plate with the standards and positively urging movement of the plate in one direction relative to the body.

4. A container filling device, comprising an elongated horizontally disposed body having a flat bottom portion and upstanding longitudinal side walls, a pair of fixed standards disposed at opposite sides of the body and extending above said walls, an elongated plate extending longitudinally of and over the body and disposed between said standards, said plate having a width facilitating its disposition between the side walls, pivot trunnions extending laterally from the sides of the plate, and means forming a combined sliding and pivotal coupling between the trunnions and the standards whereby the plate may move bodily toward and away from the body and may oscillate on an axis extending transversely of the body.

5. A container filling device as set forth in claim 4, including spring means connecting each standard with the adjacent trunnion and maintaining the plate in a predetermined position relative to the body.

6. A container filling device as set forth in claim 4, wherein the stated means coupling the trunnions with the standards comprises a slot formed longitudinally in each standard into which the adjacent trunnion extends, and resilient means connecting each standard with the adjacent trunnion, the said resilient means maintaining the plate in a predetermined position relative to the body.
